UNITED STATES PATENT OFFICE.

JOHN W. BIRDZELL, OF ARKANSAS CITY, KANSAS.

INTERNAL-COMBUSTION ROTARY ENGINE.

1,338,207.

Specification of Letters Patent. Patented Apr. 27, 1920.

Application filed January 11, 1916. Serial No. 71,509.

To all whom it may concern:

Be it known that I, JOHN W. BIRDZELL, a citizen of the United States, residing at Arkansas City, in the county of Cowley and 5 State of Kansas, have invented a new and useful Improvement in Internal-Combustion Rotary Engines, of which the following is a specification.

This invention relates to improvements 10 in internal combustion engines of the rotor type and has for its object to provide a device of this character which shall be simple, inexpensive, and efficient in construction and operation.

15 The leading feature of this invention consists in the fact that a high degree of compression of the combustible fluid is obtained and economy in the consumption of gas also provided, while initial starting means of 20 novel construction is also provided.

With the above and other objects in view my invention consists in the combination, arrangement and details of construction disclosed in the drawings and specification 25 and then more particularly pointed out in the appended claims.

In the drawings wherein similar reference characters designate similar parts throughout the respective views,

30 Figure 1 is an end elevation, partly in section, of my invention.

Fig. 2 is a side elevation thereof partly in section.

Fig. 3 is a fragmental sectional view of 35 the piston.

Fig. 4 is an enlarged horizontal cross-section of the top of the gas chest at the dotted line 4—4.

Fig. 5 is a detail view of a part of the gas 40 chest and the compressed air throttle valves.

Fig. 6 is a cross-sectional view of the compressed air-throttle valve,

Fig. 7 is a perspective view of the slide valve abutment, and

45 Figs. 8, 9, and 10 are respectively, cross-sectional views of the slide valve abutments taken on lines 8—8, 9—9, and 10—10 of Fig. 7.

In the drawings which are merely illustrative of my invention, F designates the bed-plate of the engine frame. The engine illustrated is of the tandem type, but as each engine is identically similar in construction, it is proposed to illustrate but one engine.

55 14 designates the engine casing in which a

rotor 15 revolves, the peripheral portion of which is connected with the hub by an integral series of cooling vanes 19 secured concentrically upon the shaft 10. The peripheral portion of the rotor revolvably fits 60 the casing 50 and is formed with annular groove R, U-shaped in cross-section, the annular packing rings 21 on the peripheral portion of the rotor snugly engaging the interior wall of the casing. A pair of removable flanges 18 are attached to the opposing sides of the rotor for the purpose of closing the explosion chamber of the rotor. The vanes 19 are disposed at a diagonal pitch upon the hub of the shaft 10, so as to 65 set up air currents to cool the rotor. A piston A is secured upon the rotor and extends cross-wise of each groove R and also slidably engages the interior wall of the casing. Secured laterally of the rotor upon its peripheral portion is an outwardly extending lug V so positioned relatively to the piston A as to be in back of the lug, the arrangement being such that as the rotor is making 70 its cycle of revolution, the lug V will push 75 against the roller secured to the rocker arm W which projects outside the casing 14 in the path of movement of the lug V, whereupon the arm W will be tripped and cause its inner angular portion 50 to operate the 80 slide valve D which snugly fits a passage 90 formed in a valve chest E secured upon the upper portion of the rotor casing. This slide valve is formed at its upper end with a fuel chamber K and a plug M fits the 85 outer end of this chamber securely so as to close the same, the plug also serving as a seat for one end of a coiled spring 24 positioned in the mentioned passage 90 in which the slide valve operates, the free end of the 90 spring 24 engaging the point of the screw 70 tapped into the upper end of the valve chest; the spring 24 holds the slide valve D in projecting relation in the U-shaped combustion chamber R of the rotor in a 95 manner to engage the periphery of the rotor 15, while the nose portion 50 of the rocker arm projects into a recess 80 formed in the slide valve D. The piston A is positioned in advance of the lug V just far 100 enough to assure its free passage under said passage 90 when it comes in back of the slide valve, and as the lug V is lifting the rocker arm W and the arm 50 of the latter is 105 lifting the slide valve D out of the combustion 110 chamber R.

bustion chamber of the rotor, the piston is gradually nearing this valve but when the valve has been completely lifted out of projecting position, against the tension of 5 spring 24, just then the piston A passes under said passage and as by this time the slide valve is automatically released and returns to projecting position, the piston A begins to exhaust the air in the combustion 10 chamber which intervenes between the projecting portion of the slide valve and the piston A, the exhausted air or fluid being gradually forced by piston A toward and ultimately out of the exhaust pipe 12, this 15 pipe thereby becoming heated and serving to heat compressed air conducted into the compressed-air chamber Q of the valve chest by means of the intake pipe 20, equipped with a check valve Z such as is shown in 20 Fig. 6, the shank of the valve Z being designated 3 while the spring secured to said valve is designated 100. This valve is normally open to admit compressed air into the compression chamber Q except when the air 25 in this chamber is being exhausted whereupon chamber Q is deprived of its fluid, because the valve Z is temporarily held closed owing to the suction from the engine. The compressed air is adapted to flow into a 30 mixing chamber E' at right angles to the compression chamber but in line with the passage 90, but only when the slide valve D permits. A pipe Y' leads from the compressed air chamber Q and connects with a 35 pipe C⁵ which is equipped with a check valve Z as before explained, in its casing C², and this pipe C⁵ discharges into the combustion zone of the rotor. The combustible fuel pipe I communicates with the fuel 40 chamber K formed in the valve D. When the slide valve is in position shown in Fig. 1 its port J, registering with chamber K is below fuel pipe I so no fuel can enter the valve until it is lifted far enough. There is 45 a part P' formed in the compressed air chamber Q which communicates with passage 90 and a similar port P is formed upon the mixing chamber E'. Valve D is formed with two ports N and O at right angles with 50 each other and adapted respectively when the valve O is lifted to connect ports P and P' with passage 90 in the valve at the same time that combustible fuel is being admitted into this passage 90. Formed upon valve D 55 below and out of communication with passage 90 is an angular port S and I, adapted to communicate when the valve D is in projecting position, with a port Z' formed at the lower end of the mixing chamber E', the 60 port S registering also with the port T, formed in the valve chest and connecting with pipe C⁵, which, as before explained, communicates with the combustion zone of the rotor. 65 23 designates oil cups for lubricating the driven shaft 10. The spark plug

is designated U, and is located near the pipe C⁵. It is understood that the piston A may be equipped with a packing ring. The plug M, it will be noticed, is formed with a through port L communicating at its bottom with the fuel passage K formed in valve D. There is a space above the slide valve in which it is movable and in which air is compressed by the valve D as it moves upwardly. 75

The operation of the engine is as follows:—It will be presumed that there is compressed air in the compressed air chamber Q as explained before. This compressed air is under considerable pressure and is accordingly utilized as a self-starter for the engine. By opening the valve Y, the compressed air is conducted out of chamber Q by way of pipe Y' and thence passes through pipe C⁵ into the combustion zone or grooves 80 R of the rotor, and begins to act expansively against the piston A of the rotor, thereby causing the rotor to be revolved and as it is about to complete one revolution the piston approaches in back of valve D, the lug V 85 engages and trips the rocker arm or lever W and the valve D is lifted out of the way of piston A, which passes under passage 90. As valve D is moving upwardly its port J registers with fuel inlet pipe I and fuel is 90 admitted into the fuel chamber K of said valve, and as valve D is compressing air in passage 90 as it moves upwardly, the compressed air thus generated flows freely back through the channel L into fuel chamber K 95 and creates pressure enough to cause the combustible fluid to pass out of port N in valve D; as soon as ports N and O register with ports P and P' in the mixing chamber E' and said fluid is thus compressed in 100 chamber Q. As the piston A has been exhausting the fluid in back of it and as valve Y is still open a suction has been created by way of pipes C⁵ and I in chamber Q and when the suction is broken after the 105 exhaust has been discharged, compressed air flows in this chamber Q by way of check valve Z in pipe 20—so when port O registers with port P' compressed air flows into the mixing chamber E' and mixes under 110 considerable pressure with the fuel therein. When the lug passes the rocker arm, spring 115 24 relaxes and valve D slides automatically back to projecting position upon the rotor. This will connect port S on valve D with both port Z' at the bottom of the mixing chamber E' and with port T leading to pipe C⁵ and hence the combustible mixture will pass into the combustion zone of the rotor. It should be noted that by means of the conventional expedients the spark plug U will 120 be ignited in time to explode the combustible charge initially introduced into the combustion zone of the rotor and during each 125 cycle of the engine thereafterward. 120 125 130

Numerous modifications may be resorted to in practice without departing in principle from the details of construction herein disclosed.

5 What I claim and desire patent protection on is:—

1. In an engine, in combination, a casing, a rotor revoluble therein, a fuel-mixing chamber, a compressed air chamber, a 10 spring-pressed slide valve projecting into said casing, and engaging the periphery of said rotor, a piston on said rotor slidably engaging the interior wall of said casing, means controlled by said valve for throwing said chambers open to intercommunication, and means controlled by said valve and adapted to conduct the fluid mixed into said rotor to act against said piston.

2. In an engine, in combination, a casing, 20 a rotor snugly revolving therein, and having an annular peripheral combustion chamber, a piston in said chamber moving under fluid impact, a compressed air chamber mounted at the upper end of said casing, a mixing 25 chamber formed in advance and laterally of said compressed air chamber, each chamber having a port, a valve chamber arranged opposite the foregoing chamber, a valve sliding in said valve chamber and having ports 30 adapted to connect the foregoing ports, means controlled by said rotor for controlling the operation of said valve, means controlled by said valve for connecting said mixing chamber with the combustion chamber.

3. In an engine, in combination, a casing, a valve chest secured thereabove, a rotor revoluble in said casing, said valve chest having a vertical passage, a mixing chamber arranged transversely of said passage and having a port registering therewith and a compressed-air chamber arranged longitudinally of said passage and having a port registering therewith, a slide valve snugly movable 45 in said passage, and having ports adapted to connect the foregoing ports, said mixing chamber having also an outlet port, said valve having a port adapted to register with said last-named port, and means controlled by said valve and adapted to connect the

last-named port of said valve with said rotor.

4. In an engine, in combination, a casing, a rotor revoluble therein, a valve chest in said casing, having a central valve passage, a mixing chamber transversely of said passage and a compressed air chamber longitudinally of said passage, said casing having a fluid inlet channel adjacent the valve chest, a pipe leading from said compressed air chamber to said channel, said valve chest having at its lower end a lateral channel, a pipe connecting said channel and said first pipe, a valve slideable in said passage and formed with a central gas receiving-chamber, with ports leading from said chamber to connect the mixing chamber with the compressed-air chamber, and with a port below said chamber adapted to connect said mixing chamber with said channel, and means 70 controlled by said rotor whereby said valve may connect either its first-named ports or last-named ports for communication as specified.

5. In a device as described, in combination, a casing, a valve chest therein having a valve passage communicating with said casing, a slide valve in said passage, having a gas chamber opening out of its top, a plug seated partially in said chamber and formed with a vertical duct registering with said chamber, a spring in said passage engaging said plug as a seat, said rotor having a peripheral groove, said spring causing said valve to project into said groove in engagement with said rotor, a fuel pipe communicating with said passage, said valve having a port communicating with its chamber, a mixing and a compressed air chamber, said valve having ports adapted to connect said 80 last-named chamber, a piston in said groove of the rotor, and means controlled by said rotor for raising said valve out of the path of said piston whereby the first port of said valve connects with the fuel pipe and the other ports with said chambers.
